UNITED STATES PATENT OFFICE.

ERNEST H. ASHLOCK, OF SAN DIEGO, CALIFORNIA, ASSIGNOR TO WILLIAM H. SWEET-LAND, OF SAN DIEGO, CALIFORNIA.

BODY-CONTACT DEVICE FOR CHIROPRACTIC ADJUSTMENT MACHINES.

Application filed December 12, 1922. Serial No. 606,389.

My invention relates to a body contact device for chiropractic adjustment machines and the objects of my invention are: first, to provide a contact device of this class 5 of bridged shaped and construction which when applied to the regions of the spinal column can be made to straddle the column and apply equal pressure to both sides thereof for loosening and adjusting the ligaments, muscles and tissues in the vicinity 10 of the spinal column preparatory to adjustment of the vertebrae; second, to provide a body contact device of this class of very yieldable construction so that when the same 15 is applied as stated above no injurious effects will be obtained; third, to provide a novelly constructed body contact device for chiropractic adjustment machines and fourth to provide a contact device of this class 20 which is particularly simple and economical of construction, durable, practical, efficient and which will not readily deteriorate or get out of order.

With these and other objects in view as 25 will appear hereinafter my invention consists of certain novel features of construction, combination and arrangement of parts and portions, as will be hereinafter described in detail and particularly set forth 30 in the appended claims, reference being had to the accompanying drawings and to the characters of reference thereon which form a part of this application, in which:

Figure 1 is an end view of the body contact device for chiropractic adjustment machines showing the same positioned on the end of the reciprocating plunger of the machine which plunger is shown fragmentarily and in section and showing by dotted lines 40 a receded position of portions of the contact device when contacting with the body; Fig. 2 is a side elevational view thereof shown apart from the plunger as shown in Fig. 1 and Fig. 3 is a plan view thereof.

Like characters of reference refer to similar parts and portions throughout the several views of the drawings.

The main contact member 1, plate 2, bolt 3 and the nut 4 constitute the principal parts 50 and portions of my body contact device.

The main contact member 1 is preferably made of a resilient pliable rubber and is substantially U-shaped in cross section, as shown, its width being somewhat less than 55 its length. The leg portions 1^a of the U-

shaped member 1 are slightly narrower than the cross portion 1^b which connects said leg portions. The normally upper or outer side of the member 1 is slightly curved as shown best in Fig. 1 of the drawings. A plate 2 also 60 curved downwardly is positioned adjacent the upper curved face of the member 1. A bolt 3 provided with a substantially large head is inserted through the cross connecting portion of the U-shaped member from the 65 normally lower or inner side thereof and extends through the same and through the plate 2 positioned against the outer side. The member 1 and the plate 2 are held in position relatively to each other by the bolt 70 extending therethrough and by the nut 4 screwed on said bolt. It will be noted that the screw portion of the bolt extends a considerable distance beyond the nut 4 and thus provides ample means for securing the 75 body contact member as described to the reciprocating plunger A of a chiropractic adjustment machine, for which I have made separate application for Letters Patent, filed in the United States Patent Office, October 80 9, 1922, Serial No. 593,448, the outer end of said plunger being provided with an internally threaded recess.

Though I have shown and described a particular construction, combination and arrangement of parts and portions I do not wish to be limited to this particular construction, combination and arrangement but desire to include in the scope of my invention, the construction, combination and 85 arrangement substantially as set forth in the appended claims.

It is obvious from this construction that there is provided a contact device for chiropractic adjustment machines of bridged 90 construction which when applied to the regions of the spinal column can be made to straddle the column and apply equal pressure to both sides thereof loosening and adjusting the ligaments, muscles and tissues 95 in the vicinity of the spinal column, preparatory to the adjustment of the vertebrae; that I have provided a contact device of this class which is particularly resilient of construction and will yield when applied to the 100 body or bones of the body and is so constructed as to straddle sore or injured portions of the body; that there is provided a novelly constructed body contact device for 105 chiropractic adjustment machines and that 110

there is provided a contact device of this class which is particularly simple and economical of construction, durable, efficient, practical and which will not readily deteriorate or get out of order.

Having thus described my invention what I claim as new and desire to secure by Letters Patent, is:

1. In a device of the class described, the combination with a vibrating member of a substantially U-shaped yieldable rubber body contact member; the leg and connecting portions thereof being of integral construction and the length thereof being greater than the width, a reinforcing resilient plate positioned on the back side of said body contact member; and a bolt means extending through the connecting portion of said body

contact member and said plate, securing the same together and adapted to be secured to one end of said vibrating member.

2. In a device of the class described, the combination with a vibrating member, of a yieldable channel shaped body contact member made from resilient material, a resilient plate positioned against the outer side of said yieldable body contact member and a supporting member securing said contact member and said plate together and provided with a securing portion extending beyond said plate adapted to secure said supporting member to said vibrating member.

In testimony whereof, I have hereunto set my hand at San Diego, California this 5th day of December 1922.

ERNEST H. ASHLOCK.
